VALVE

James H. Miller, Jackson, Mich., assignor, by mesne assignments, to Scaife Company, Oakmont, Pa., a corporation of Pennsylvania

Application October 7, 1948, Serial No. 53,269

3 Claims. (Cl. 137—112)

This invention relates to systems for providing automatic heat for both space heating and domestic hot water and is particularly directed to automatic bypass valving arrangements which are efficient and leak proof.

Systems wherein water from the boiler is utilized for heating the domestic hot water supply and the space heating radiators of a building are known. In most of these systems, the boiler water is diverted to bypass the radiators when no heat is required in the space to be heated. These systems provide special valves controlled by the fluid pressure in the system for closing off either the bypass or conduit connected to the radiators depending on the conditions of operation. I have investigated such systems and found that their valving arrangements are inadequate to prevent leakage of boiler water through the closed valve structures, and the invention contemplates a valve arrangement which will efficiently accomplish this purpose.

This valve of the invention, which will be described in detail below, is very important to efficient operation of the system. When the thermostat in the building calls for heat for the space heating system, flow of hot water from the boiler through the radiators dynamically maintains my valve in a position where it tightly closes the bypass, this being essential in order to obtain efficient heating of the space heater system. When this thermostat shuts down, hot water circulation through the radiators stops and my valve is actuated by static system pressure to close the return line from the radiators and open the bypass, so that the boiler water is now circulated to heat the domestic hot water supply only. It is important during this period that there be no bleeding of hot water into the space heater system in order to obtain efficient and adequate heating of the domestic hot water supply, particularly in the summer time when space heating is never required, and my valve accomplishes this action.

It is, therefore, a major object of my invention to provide a combination domestic hot water supply and space heater system wherein a novel valve arrangement is provided for controlling the bypass between the two during automatic operation.

It is a further object of my invention to provide a novel combined space heating and domestic hot water supply system wherein a coil for heating the domestic hot water is disposed in an expansion tank for the boiler.

It is a further object of my invention to provide a novel fluid pressure actuated shiftable valve for a bypass across the space heating portion of a combined boiler and domestic hot water heater system adapted for assuring efficient sealing in either position of the valve.

It is a further object of my invention to provide a valve comprising a coupling member having in novel combination offset passages and inclined valve seats adapted to be closed one or the other by a freely swingable valve responsive to fluid pressures in the system.

The above and other objects of the invention will become apparent as the description proceeds in connection

2

with the appended claims and the annexed drawings wherein:

Figure 1 is a side elevation, partially diagrammatic and partially in section, illustrating a combined space heating and domestic hot water supply system embodying the invention;

Figure 2 is a cross section through the novel coupling of the invention;

Figure 3 is a front elevation, viewed from the right in Figure 2, of the coupling of Figure 2;

Figure 4 is a rear elevation of this coupling of Figure 2 which is symmetrical, the left half only being shown; and

Figure 5 is a section on line 5—5 of Figure 3, illustrating the manner in which the flap valve element is suspended in the coupling.

Referring to Figure 1, a boiler indicated at 11 comprises a casing 12 supported on a suitable base 13 and is closed at the bottom by a hearth 14 and at the top by a cover 15. A suitable liquid fuel burner such as a rotary wall flame oil burner may be supported to project through hearth 14 for heating water within a cylindrical coil 16 disposed within the casing 12 and comprising a helical coil of copper tubing of high heat resistance and high heat conductivity.

An expansion tank 17 is supported in spaced relation above the boiler 11, as by a plurality of uprights 18 welded at opposite ends to casing 12 and the expansion tank. The upper end of coil 16 emerges through casing 12 at an elbow coupling 19 which is connected by an upright conduit 21 to a similar coupling 22 entering the expansion tank 17. A flue outlet 23 is provided for casing 12, whereby the products of combustion from the burner after passing through the casing and heating the coil 16 may be discharged into the chimney.

The lower end of coil 16 is connected to a special coupling indicated at 24 secured to casing 12 in suitable manner. This coupling is generally a T-coupling and is preferably arranged with its arms arranged horizontally, one arm being connected to the lower end of coil 16 within casing 12 and the other arm being connected by a conduit 25 to a suitable pump 26 which in turn is connected by conduit system 27 to the radiators or other space heating devices indicated at 28. The angularly disposed leg of the coupling is preferably disposed upright and connected to a vertical bypass conduit 29 which rises just outside casing 12 to a suitable T-coupling 31 that has its opposite arms connected respectively to the interior of expansion tank 17 and a conduit 32 leading to space heating device 28. The interior of expansion tank 17 contains a coil of tubing 33 the opposite ends of which extend in water tight manner through the walls of expansion tank 17 to conduits 34 and 35 that are connected to a hot water storage tank 36 from which domestic hot water may be drawn by suitable pipe connections.

In practice, pump 26 is under control of a thermostat which is arranged within the space to be heated by the devices 28 so that the pump is idle or operating depending upon the demand for heat from that space. When space heating is demanded by this thermostat, pump 26 initiates operation to promote circulation of hot water as indicated by the full line arrows in Figure 1. Starting at pump 26, hot water flows through conduit 25, the arms of coupling 24, through coil 16 and conduit 21 into the expansion tank 17, and through conduit 32 into the space heater devices 28, from which it flows through conduit 27 back to the pump. A suitable valve arrangement in coupling 24 seals off the lower end of conduit 29 as will be explained. This circulation will keep up as long as the thermostat demands heat.

After the space has been adequately heated, the ther-

mostat will cut off the pump motor and provision is made in the coupling 24 that the valve element, which has hitherto sealed the bypass 29 against bleeding of hot water, is shifted to seal the return conduit 25 against bleeding of hot water from the boiler. Under these latter conditions, the hot water which is heated in coil 16, the burner being also controlled by a further thermostat in storage tank 36 particularly for summer operation, circulates primarily by convection up through conduit 21 into expansion tank 17 and downwardly through bypass conduit 29 as indicated by the dotted arrow, through coupling 24 and back into the lower end of the coil 16.

A preferred embodiment of the associated passage and valve construction in coupling 24 is illustrated in Figures 2-5. Coupling 24 comprises an upright leg 37, and a substantially horizontal branch portion comprising offset outer and inner arms 38 and 39 respectively. The upper end of leg 37 is provided with a flange 41 for securing the lower end of bypass conduit 29 and terminates within the coupling in a valve seat indicated at 42, the plane of which valve seat is disposed at an acute angle with respect to the axis of leg 37. The outer end of arm 38 is provided with a threaded flange 43 for connection with the return line conduit 25 and is formed within the coupling with an apertured internal wall 44 providing a flat valve seat 45 inclined to the axis of arm 38 and surrounding the passage 46 through wall 44 for a purpose to appear.

The end of arm 39 comprises a flange 47 internally formed with an annular recessed shoulder 48 further recessed to provide an annular shoulder 49. As illustrated in Figure 4, arm 39 has a rectangular cross section 50 which is adapted to register with a similar coupling attached to the lower end of coil 16 within casing 12. The axes of arms 38 and 39 are preferably parallel and horizontal, but they are offset a material distance as indicated at d in Figure 2. As will appear, this offset has definite correlation with the angle at which the valve element is disposed for providing efficient control of flow of water through the coupling. Passage 46 forms a restriction that provides a steady flow of water against valve element 61 to assure closing of the valve during pump operation.

Above arm 38, coupling 24 is formed with a boss 51 which is internally recessed to provide a valve element 45 pivoting chamber 52. The opposite side walls of the boss (Figure 5) are provided respectively with a bore 53 and a coaxial threaded aperture 54 for receiving respectively a press fitted bushing 55 and a threaded bushing sleeve 56 for supporting opposite ends of a valve element supporting shaft 57 that has its axis perpendicular to the plane containing the axis of coupling leg 37. The outer end of sleeve 56 is formed with a head 58 for limiting inward movement of the sleeve and for enabling its withdrawal when it is desired to remove shaft 57.

The valve element preferably comprising an integral plate or sheet 61 of light metal such as steel or aluminum which is flat on opposite sides and bent at its upper end to form an inclined portion 62 where it extends into chamber 52. Valve element 61 terminates in a hinged portion 63 when it is curled part way around the shaft 57 to be thereby freely pivotally suspended from shaft 57 and with a limited range of movement between planar valve seats 42 and 45 as determined by the fluid pressures within coupling 24. The flat opposite sides of valve element 61 rest on valve seats 42 or 45 during operation.

I have discovered that if, as in the usual T-coupling structure, the valve face 42 is substantially horizontal and the arms 38 and 39 are coaxial, valve element 61 cannot be maintained in absolutely sealed position on valve seat 42, since the force component of fluid pressure due to fluid flow through arm 38 in the direction of the arrow in Figure 2 would not be sufficient to keep valve element 61 tightly on seat 42 against the head of water

in bypass conduit 29, and there would be undesired bleeding of hot water into the conduit 29.

According to the present invention therefore, I arrange valve seat 42 at a sufficient angle that the fluid pressure exerted by water passing through arms 38 and 39 of the coupling when pump 36 is operating is sufficient to hold valve plate 61 tightly on seat 42. I further discovered that if arm 39 should be disposed coaxial with arm 38, the introduction of the inclined valve seat arrangement at 42 effectively restricts the volume of flow through the coupling. Hence, in order to provide for unrestricted flow through the coupling without undesirable increase in the size of arm 39, and at the same time provide a satisfactory valve angularity, I provide the above described offset between arms 38 and 39, whereby, although the water stream through arm 38 is deflected by the closed valve plate 61, the offset of arm 39 provides sufficient cross sectional area through the coupling so there is no restriction of the stream passing through the coupling. The slight deflection provided by the offset has no appreciable effect on the velocity or other flow characteristics of the water stream as far as the system is concerned.

The angle to the vertical at which valve seat 42 is disposed is critical in determining the sealing action of valve element 61. As this angle is increased, the available valve closing pressure component from the stream entering arm 38 is reduced and the effective passage size through the coupling arms is enlarged. On the other hand, as this angle is decreased, the fluid pressure component available to press valve element 61 against seat 42 is increased but the passage through the coupling may be restricted, requiring further offset of arms 38 and 39. Thus the choice of the optimum angle for valve seat 42 depends upon the available fluid pressures in the system in which the coupling is used. The angularity of valve seat 45 to the vertical is of course always less than valve seat 42 and sufficient that valve element 61 be pressed tightly on seat 45 by the head of water in bypass conduit 29. Preferably the angularity of seat 45 to the vertical equals the angularity of valve element portion 62 to the vertical when the valve element is in the full line position of Figure 2 so that under such conditions the plane of valve portion 62 is parallel to the plane of seat 45, and when the valve element is in the dotted line position the valve portion 62 is substantially vertical so that the weight of valve element 61, although small, contributes as much as possible to the valve attaining that dotted line position when the pump 26 ceases operation.

In one practical embodiment of the invention, as disclosed, the valve seat 42 is disposed in a plane at an angle of substantially $67\frac{1}{2}$ degrees to the vertical with excellent results and effective sealing of the bypass was obtained. In this structure, valve seat 45 is disposed at an angle of substantially 37 degrees to the vertical. The distance d in this embodiment is $1\frac{1}{16}$ inch.

When the pump 26 is shut off, the kinetic head delivered through the conduit 25 is eliminated and the combined static head present in bypass conduit 29 and the weight of the valve element 61 becomes effective to displace valve element 61 from seat 42 into the dotted line position illustrated in Figure 2 where it seals the valve seat 45.

Valve seats 42 and 45 are preferably circular annular areas, and the associated contacting portion of valve 61 is a circular disc as illustrated.

I have thus provided an automatically operated valve which effectively and automatically prevents undesired bleeding of hot water in the system. The internal construction of the coupling is mechanically simple, and it is easy to repair or replace the valve element 61 should it become corroded or deformed.

The invention may be embodied in other specific forms without departing from the spirit or essential characteristics thereof. The present embodiment is therefore to be considered in all respects as illustrative and not restrictive.

tive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. A valve comprising a modified inverted T fitting having a generally horizontal through passage provided by hollow inlet and outlet arms having vertically offset axes, means in said fitting providing a substantially upright passage intersecting and entering said generally horizontal passage from above between said arms, a valve seat on the bottom of said upright passage inclined with respect to horizontal, a valve seat on the inner end of said inlet arm inclined in the same direction as but at a greater angle with respect to the horizontal than said valve seat on the bottom of the upright passage, said inlet valve seat opening being of smaller cross-sectional area than said outlet arm passage, and a freely pivoted light weight valve element within said fitting adapted to be positioned against either of said seats, depending upon fluid flow conditions, said valve element being normally gravity urged onto said valve seat at the inner end of the inlet arm when there is no fluid flow through said horizontal passage and always remaining in the direct path of inlet fluid flow so as to be urged and held against the upper passage seat when fluid under pressure is forced through said passage.

2. In a flow control valve, a modified inverted T fitting having a generally horizontal passage comprising inlet and outlet arms having vertically offset axes and an upper passage opening into the horizontal passage from above between said arms, valve seats at the inner ends of said inlet arm and said upper passage, said seats being inclined in the same direction at different angles and each seat being inclined with respect to its associated passage, and a freely pivoted valve element adapted to be positioned against either of said seats depending upon fluid flow conditions in said valve comprising a single thickness thin metal plate of light weight, said valve element normally tending to rest by gravity on said inlet seat and lying in the path of fluid entering through said inlet arm valve seat but in non-obstructing relation with respect to said outlet arm when urged and held against said upper passage

seat by fluid flow through the passage, and said outlet arm being disposed at a lower level and providing a larger cross sectional area of passage than the opening of the valve seat of said inlet arm whereby fluid flow through said horizontal passage is substantially unrestricted.

3. A fluid pressure actuated control valve comprising an inverted modified T fitting having a generally horizontal through passage provided by inlet and outlet arms, the outlet arm being offset to a lower level than said inlet arm, means defining a substantially vertical passage opening into said horizontal passage between said arms, a valve seat across the end of said vertical passage within the fitting disposed at an acute angle with respect to the vertical passage axis, means defining a valve seat at the inner end of said inlet passage disposed at an acute angle with respect to the vertical, said seats being inclined in the same direction and the first mentioned acute angle being the greater, and a freely pivoted valve element within said fitting adapted to swing into engagement with either valve seat depending upon flow conditions, said valve element when disposed against the vertical passage valve seat lying in the path of the fluid entering said inlet arm, and said inlet valve seat comprising an apertured wall extending across said inlet arm, the aperture providing an inlet area of reduced size with respect to the outlet arm cross-sectional area, whereby substantially unimpeded flow is obtained through said valve.
